UNITED STATES PATENT OFFICE.

DAVID WILLIAM ALLMAN, OF TORONTO, ONTARIO, CANADA.

WATER-HEATER.

938,623.

Specification of Letters Patent. Patented Nov. 2, 1909.

Application filed March 23, 1908. Serial No. 422,791.

To all whom it may concern:

Be it known that I, DAVID WILLIAM ALLMAN, a subject of the King of Great Britain, resident of the city of Toronto, in the county of York, Province of Ontario, in the Dominion of Canada, have invented certain new and useful Improvements in Water-Heaters, of which the following is a specification.

The invention relates to improvements in water heaters, as described in the present specification and set forth in the accompanying drawing that forms part of the same.

The invention consists essentially in the novel construction and arrangement of parts, whereby the water is circulated throughout a plurality of chambers subjected to heating gases and the boiling portion separated from the cooler portion and whereby the gases are continuously circulated around the water chambers.

The objects of the invention are, to obtain a continuous supply of boiling water and replenish the water drawn off with a fresh supply without affecting the boiling water, to insure the water against contamination through contact with injurious gases or polluted air, to effect an economy of fuel, and to devise a safe and convenient device for boiling water, of simple, cheap and durable construction.

The drawing represents a vertical sectional perspective view of my device.

Referring to the drawing, 1 is the outer shell of the heater, preferably circular in form and having a dome shaped upper end 2 above the waist 3, said dome 2 having a central circular opening 4 and the edge of said opening flanged outwardly.

5 is a hollow flat base on which the shell 1 stands, the said base closing in the lower end of said shell and having a circumferential row of air holes 6 in the outer edge communicating with the outside air and a circular row of short tubes 7, projecting upwardly through the center of the upper plate. The passage of air through the holes 6 is regulated by a sliding ring 8 having holes registering with the holes 6.

9 is a gas burner preferably circular in form and supported on the top of the base 5

immediately above the air tubes 7 and connected to a suitable gas supply by a pipe 10. 11 is a pilot burner centrally arranged in relation to the burner 9 and independently connected to the gas supply by the pipe 12. 55

13 is an opening through the outer shell 1 through which a taper may be inserted to light the pilot burner.

14 is a spherical shell of smaller diameter than the dome shaped portion of the shell 60 1 having a circular opening through the top and its walls flared outwardly and flanged over the outwardly flanged edge of the shell 1 surrounding the opening 4 and supporting the said shell 14 centrally within the dome 2. 65

15 is an annular casing of smaller outside diameter than the inside of the shell 1 supported centrally within the lower cylindrical portion of said shell immediately above the burner 9, the center opening 16 through said 70 casing being preferably of about the same diameter as the outer ring of the said burner and forming a flue to said burner, the said casing being supported in its suspended position by suitable supports 17 secured thereto 75 and to the shell 1 in any suitable manner.

18 is a tube secured to and extending upwardly from the annular casing 15 and through the spherical shell 14 and communicating with the interior of said casing 15 80 and having a suitable coupling 19 arranged intermediate of its length.

20 is a spherical shell of smaller diameter than the shell 14, rigidly secured to the inwardly extending end of the tube 18 and 85 supported centrally within the shell 14 and forming a water chamber 21 between its outer wall and the inner wall of the said shell 14, said shell 20 having a circular opening through the top thereof and the wall of 90 said opening flanged outwardly.

22 is a half spherical shell of slightly smaller diameter than the shell 20 having its edge flared outwardly and secured to the inner surface of the said shell 20 forming an air space around the lower half of the said shell 20, the tube 18 extending through said shell 22 and rigidly secured thereto and communicating with the interior thereof beyond 95 said air chamber. 100

- 23 is a spherical shell of smaller diameter than the shell 20 having a circular opening in the top thereof and its walls flared outwardly and secured in a bead to the upwardly flanged edge of the shell 20 and supported therefrom centrally within the said shell 20 and forming a water chamber 24 between the inner walls of the shells 20 and 22 and the outer wall thereof and a central receiving water chamber 25, the outwardly flaring walls having a circular row of holes 26 therethrough near the upper edge forming a means of communication between the chambers 24 and 25.
- 27 is a pipe secured to the shell 23 at the bottom thereof and extending through the chamber 24 and the tube 18 into the interior of the annular casing 15, the said pipe being supported and held centrally within the tube 18 by a perforated shield 28 rigidly secured thereto and to the interior surface of the shell 22.
- 29 is a pipe extending upwardly from the top of the annular casing 15 and through the shells 14, 20 and 22 and forming a communication between the interior of the casing 15 and the chamber 24, the upper end of said pipe extending into said chamber and considerably higher than the opening to the tube 18 at the bottom of said chamber. This arrangement of the pipe 29 is very important, for, on the heating of the water within the casing 15, it immediately rises and as the column of water above the pipe 29 is much lighter than the column of water above the pipe tube 18, the water rises easily in the pipe 29 and returns through the tube 18 establishing a circulation of water in the casing 15 and chamber 24.
- 30 is a cup shaped shield or baffle plate arranged in the lower portion of the water chamber 21 and dividing the said lower portion into the upper and lower compartments 31 and 32 respectively.
- 33 is a cylindrical casing centrally arranged within the opening 16 through the annular casing 15 and having a vertical flue 34 extending through the center thereof from the bottom and communicating with a transversely arranged flue 35 near the top thereof and extending to and through the sides of said casing.
- 36 is a pipe secured to the top of the casing 33 and extending into the spherical shell 14 centrally in its under side and establishing a circulatory communication between the interior of the casing 33 and compartment 32 of the chamber 21, the said pipe having a suitable coupling 37 in the length thereof. The casing 33 is connected to the annular casing 15 by a pipe 38 entering said casing 33 at the bottom and communicating with the interior of said casing 15 through its adjacent side close to the bottom.
- 39 is the draw off pipe extending through the shell 14 and the shield 30 and opening into the compartment 31 of the chamber 21 and leading therefrom through the outer shell 1 to the tap 40. The tap 40 is of the ordinary form of plug cock having a hollow threaded stem 41 extending upwardly therefrom and a handle 42 rigidly secured to said stem.
- 43 is a hollow threaded cap threaded on to the stem 41 of the tap 40 having a central squared orifice in the top thereof and rigidly secured to said threaded stem by a suitable set screw 44.
- 45 is a valve or tap of any suitable form having a screw spindle and adapted to open and close quickly on a slight turning of said spindle.
- The spindle 46 is squared at its outer end and extends through the squared orifice in the cap 43 turning therewith on the turning of the tap 40 and moving easily in the hollow spindle of said tap 40 so that there is no strain on the tap 40 or draw off pipe 39. The spindle 46 may be adjusted as desired, in order to regulate the flow of water through the tap 45, by loosening the set screw 44 and turning the cap 43 to change the relative location of the valve to the plug of the tap 40. The thread of the spindle 46 is sufficiently steep so that, on the turning of the tap 40 to its side open position, the tap 45 will be opened full and on the closing of the tap 40 the tap 45 will shut off the supply. The tap 45 may be opened, however, and the tap 40 retained closed, so that the heater 100 may be filled when empty, as the tap 40 turns in both directions past its open position, therefore if turned in one direction it will close the tap 45 but if turned in the other will merely open the tap 45 a little farther. The tap 45 is connected through a pipe 47 to a suitable water supply and a pipe 48 supported in a swivel joint 49 in said tap 45 carries the supply of water to and through a suitable filter 50 having its discharge end extending centrally over the opening 4 in the shell 1.
- 51 is a cup shaped cap closing the opening from the water chambers 21 and 25 and having an outwardly flaring edge 52 extending over the edge of said opening and resting on a ring 53 of asbestos or other suitable heat non-conducting material.
- 54 is a pipe secured to and extending downwardly from the cap 51 into the water chamber 25, the lower end being a considerable distance below the holes 26 in the shell 23, and conducting the water flowing from the filter into the said chamber.
- 55 is a screen of fine wire or other suitable material, placed within the bottom of the cap 51 to prevent the ingress of foreign matter to the water chambers.
- 56 is a glass tube secured to the draw off pipe 39 and extending vertically upwardly

therefrom outside of the shell 1 and forming a water gage to indicate the level of the water within the shells of the device.

In order to cleanse the water chambers 5 and to remove stale water from the heater I provide a drain tap 57 connected by a pipe 58 extending through the shell 1 and into the annular casing 15 at the bottom end.

In order to fill the heater the handle 42 is 10 turned to open the tap 45 the tap 40 being left closed. The water flows through the pipe 48 and the filter 50 and is discharged into the central water chamber 25 from whence it flows into the annular casing 15 15 through the pipe 27. The water then rises through the tube 18 and pipe 29 and also from the pipe 36 leading from the cylindrical casing 33, filling the water chambers 21 and 24 at the same time, and when said 20 chambers are filled to the desired level, that is, level with the holes 26 in the shell 23, the water is turned off and the heater is ready to be placed in operation.

The gas to the pilot burner is first turned 25 on and lighted through the opening 13 in the shell 1. The gas to the burner 9 is then turned on, igniting from the pilot. The flame and heated gases from the burners 9 and 11 rise through the flue 16 in the casing 15, passing through the flues 34 and 35 in the casing 33 and also around the outside thereof and subjecting the water contained in said casing to a very great heat. The heated gases then strike against the 30 under surface of the spherical shell 14 and spread around said shell subjecting its surface to an intense heat.

The heated gases rising to the top of the chamber between the shell 14 and the outer shell 1 become gradually cooled as they get 40 near the top and as there is no outlet at the top a return circulation of the heated gases is immediately commenced, the cooler gases passing down close to the outer shell and, 45 falling below the waist 3, continue downwardly past the outer wall of the annular casing 15 from whence they are drawn inward to the center by the draft created by the burner and passed again through the 50 flame. It will thus be seen that a continuous circulation of the heating gases is maintained and all particles of carbon are absolutely destroyed and consequently there is no escape of partly consumed gas from the 55 device. Any oxids formed in the process of combustion merely fall to the base 5 and may be cleaned off from time to time by removing said base.

Sufficient air to maintain the proper combustion of the gases in the burner is allowed 60 to enter through the holes 6 and tubes 7 in the base 5, the supply of air being regulated by the sliding ring 8. When the heat is first turned on and the water in the heater is 65 cold, condensation may occur but any mois-

ture so formed will merely fall on the base and eventually be evaporated.

The volume of water within the casing 33 is very small and being subjected to the heating action of a large area affected by 70 the heated gases, rises quickly through the pipe 36 to the lower compartment 32 of the water chamber 21 and is subjected to a further heating process and as the strata of water in said compartment is very shallow 75 and spread over a large heating area, it is quickly heated to the boiling point. When the water in the compartment 32 is heated to the boiling point, a supply of boiling water may be obtained from the tap 40. The 80 boiling water flows into the compartment 31 to the draw off pipe and as the upper surface of the said chamber is insulated from the cooler water in the chamber 24, the boiling water is not affected.

The supply of water within the heater is replenished simultaneously with the drawing of water from the compartment 31, the supply flowing through the pipe 48 and filter 50 into the inner shell 23, from whence 90 it flows through the pipe 27 to the annular casing 15. The water in the annular casing being subjected to the intense heat of the gases passing upwardly through the flue 16 and downwardly around the outside thereof, is heated very quickly and rises through the pipe 29 to the chamber 24 and circulates through said chamber to and through the tube 18, returning therethrough to the said casing 15.

The water within the casing 33 and the lower compartment 32 of the chamber 21 is heated and expanded much more rapidly than the water in the other portions of the device and therefore the water drawn from 105 the upper compartment 31 of the chamber 21 is water expanded from the main body to the boiling point. As the water rises from the cylindrical casing 33 a fresh supply is drawn in at the bottom through the pipe 38 110 from the casing 15 and consequently the supply of water to the said casing 33 is well heated before entering said casing, therefore there will be no danger of injuring the said casing 33 through too rapid expansion.

In the event of the heater being left for any length of time with the burner lighted, all the water in the chamber 21 will be raised to boiling point, and as the said chamber is not closed at the top the water is free to expand and overflow the edge of the shell 23 into the fresh water in the chamber 25. The temperature of the water in the casing 15 and chamber 24 also rises very quickly, and, 120 on account of the circulatory action, is maintained at an almost uniform temperature. On the water in the chamber 24 becoming heated it expands and flows through the holes 26 into the chamber 25. It will therefore be seen that the hot water is not affected 130

in any way by the cooler body of water but any excess of hot water assists the heating of the fresh supply.

On the water in the chamber 21 rising to 5 boiling point, steam will be generated, but as the steam rises and contacts with the cool surface of the cap 51 it is condensed and falls into the chamber 25 effecting a partial distillation. No steam can escape through 10 the opening in the cap 51 as the pipe 54 extends below the surface of the water in the chamber 25 and is therefore perfectly sealed. In the event of the pressure rising, however, the cap 51 will rise from its seat and allow 15 the steam to escape. This is a very important feature, as it renders accidents through an undue accumulation of steam, impossible. Another, and the most important feature of safety is, that cold water cannot be brought 20 into contact with any surface directly in contact with the heated gases and therefore the danger of explosion is entirely obviated. The cold water first enters the central receiving chamber 25 and flows into the casing 25 15 mixing with the large body of water in said casing which cannot be emptied from the tap 40 as it is below the level of said tap. The water is then partly heated before it can enter the central heating chamber 33 and 30 raised in said chamber almost to boiling point before it can enter the compartment 32 and as the draw off pipe is connected to the compartment 31 it will be seen that the compartment 32 can never be emptied from the draw off tap. It is possible, however, that, 35 through carelessness, all the water within the spherical casings may be allowed to evaporate but the water within the central casing 33 will then be boiling or practically so and 40 the flow of such water into contact with the shell 14 will not result in any harm. The gage glass should, however, obviate any such occurrence as the level of the water may always be readily seen.

With this device, the water, when once heated, may be maintained at the boiling point with the main burner turned off and unless the demand is very great the pilot burner furnishes sufficient heat to supply the 50 demand but if a considerable amount of boiling water is drawn off or wanted, the main burner may be turned on and a constant supply furnished. The supply of boiling water is not dependent on the head of 55 water in the supply chamber being maintained for the said supply is due to the expansion of the whole body of water in the device and if necessary a much greater quantity may be drawn off than is admitted until 60 the upper chambers are emptied.

A gas heater is shown and described as the heating means used, but it must be understood that oil or electric heaters of any suitable construction may be used if desired.

65 It is preferable to introduce the fresh

supply of water into the chamber 25 but this chamber could be eliminated and the supply carried directly to the annular casing 15 without departing from the spirit of the invention.

The form of the invention shown and described in detail is particularly adapted for restaurant and hotel work where it may be placed on a counter, but, with but a slight change it may be adapted for use for domestic purposes, that is to say, it may be readily applied to heating water for the general supply of dwellings and other buildings the essential feature of its adaptability for such purposes being in the final heating of a small body of water and elevating it continuously, replenishing the supply in such a manner as not to affect the finally heated water.

What I claim as my invention is:—

1. In a water heater, the combination with an outer shell and a suitable heat generator, of an annular water chamber supported above said heat generator and forming a central flue for the heating gases and with said outer shell a side return heat passage, said passage communicating with said central flue at the top and bottom, a plurality of water chambers arranged one within the other and supported above said annular chamber, the outer of said chambers with said outer shell forming an annular passage for the heating gases, said annular passage communicating with said central flue and side return passage, means for conveying a supply of water to said annular chamber through said upper chambers, and means supported in said central flue for conducting the water from said annular chamber to the outer of said upper chambers.

2. In a water heater, the combination with an outer shell and a suitable heat generator, of an annular water chamber supported above said heat generator and forming a central flue for the heating gases and a side return heat passage, said passage communicating with said central flue at the top and bottom, a plurality of water chambers arranged one within the other and supported above said annular chamber, the outer of said chambers with said outer shell forming an annular passage for the heating gases, said annular passage communicating with said central flue and side return passage, means for conveying a supply of water to said annular chamber through said upper chambers, and a water chamber supported in said central flue and connected at its lower end to the lower end of said annular chamber and at its upper end to the bottom of said upper casing.

3. In a water heater, the combination with an outer shell and a suitable heat generator, of an annular water chamber supported within said shell above said heat generator

- and forming a central flue for the heating gases, a water chamber supported in said central flue and communicating with said annular chamber, a water chamber supported above said annular chamber and communicating with the chamber supported in said central flue, a water chamber supported within said upper chamber and communicating with said annular chamber, and means 5 for conveying a supply of water to said annular chamber through said upper chambers.
4. In a water heater, the combination with an outer shell and a suitable heat generator, of an annular water chamber supported within said shell above said heat generator and forming a central flue for the heating gases, a water chamber supported in said central flue and communicating with said annular chamber, a water chamber supported above 10 said central passage and communicating with the chamber supported in said central flue and having a pipe leading from the bottom thereof through said outer shell, a water chamber supported within said upper chamber and communicating with the said annular chamber and providing for the circulation of the water in said annular chamber, and a water receiving chamber supported within the inner of said upper chambers and communicating with said annular chamber 15 and a water supply.
5. In a water heater, the combination with an outer shell and a suitable heat generator, of an annular water chamber supported within said shell above said heat generator and having a central heat flue therethrough, a water chamber supported in said central flue and communicating with said annular chamber, a water chamber supported above 20 said central flue and communicating with the chamber supported in said central flue and having a pipe leading from the bottom thereof through said outer shell, a casing inclosed within said upper water chamber and having a double wall inclosing a heat insulating space and supported within said upper chamber and forming an inner water chamber and communicating with said annular chamber, and a water receiving chamber supported within said insulated water chamber and communicating with said annular chamber and a water supply.
6. In a water heater, the combination with an outer shell and a suitable heat generator, of an annular water chamber supported within said shell above said heat generator and having a central heat flue therethrough, a water chamber supported in said central flue and communicating with said annular chamber, a water chamber supported above 25 said central flue and communicating with the chamber supported in said central flue, an insulated casing supported within said upper chamber and forming a water chamber and communicating with said annular 30 chamber, a baffle plate supported within the outer of said upper chambers and dividing the interior thereof into upper and lower compartments, a pipe leading from said upper compartment and extending through the outer shell, and a water receiving chamber supported within said insulated chamber and communicating with said annular chamber and a water supply.
7. In a water heater, the combination with an outer shell and a suitable heat generator, of an annular water chamber supported within said shell above said heat generator having a central heat flue therethrough, a water chamber supported in said central flue and communicating with said annular chamber, a water chamber supported within said outer shell above the annular chamber and with said outer shell forming a heat passage, 35 said upper chamber communicating with the chamber supported in the central heat flue and having an opening through the top thereof, an insulated water chamber centrally supported within said upper chamber and communicating with said annular chamber and having an opening in the top thereof, a baffle plate supported between the inner wall of said upper chamber and the outer wall of said insulated chamber and forming upper and lower compartments, a pipe leading from the upper of said compartments and extending through the outer shell, a central water receiving chamber having an open top and supported from said insulated chamber and communicating with said annular 40 chamber and with a water supply, said receiving chamber having orifices through the wall thereof adjacent to the top communicating with said insulated chamber, and means for closing the opening in the top of the outer upper chamber.
8. In a water heater, the combination with an outer shell and a suitable heat generator, of an annular water chamber supported within said shell above said heat generator having a central heat flue therethrough, a cylindrical water chamber supported in said central flue and connected at its bottom end to said annular chamber by a suitable pipe and having a vertical flue extending upwardly from the bottom and a transversely arranged flue communicating with said vertical flue, a water chamber supported above said cylindrical chamber and communicating therewith and having a pipe leading from the bottom thereof and extending through said outer shell, and means for conveying a supply of water to said annular chamber through said upper chamber.
9. In a water heater, an outer shell having an orifice in the top thereof, a heat generator, an annular water chamber supported within said shell above said heat generator and having a central heat flue therethrough, a water chamber supported in said central flue and communicating with said annular chamber.

- flue and communicating with said annular chamber, a water chamber of smaller diameter than the upper end of said outer shell having an orifice through the top thereof and its walls flaring outwardly and secured to said outer shell around the orifice in the top thereof and communicating with the water chamber supported in said central flue and having a pipe leading from the bottom thereof through said outer shell, a water receiving chamber supported within said upper chamber and communicating with said annular chamber, a cap closing the orifice in the top of said upper water chamber and having a pipe extending downwardly from the bottom thereof and projecting into said water receiving chamber, and a water supply pipe leading to and discharging into said cap.
10. In a water heater, the combination with an outer shell and a suitable heat generator, of an annular water chamber supported within said shell above said heat generator and having a central heat flue therethrough, a water chamber supported above said central heat flue and communicating with said annular chamber and having a pipe leading from the bottom thereof through said outer shell, an insulated water chamber supported within said upper water chamber and having a pipe leading from the bottom thereof and communicating with said annular chamber and a pipe leading from above the bottom thereof and communicating with said annular water chamber, a water receiving chamber supported within said insulated chamber having a pipe leading from the bottom thereof and communicating with said annular chamber, and a water supply pipe discharging into said receiving chamber.
11. In a water heater, an outer shell supported on a suitable base, a suitable heat generator supported on said base, a plurality of casings supported within said outer shell and arranged one within the other and forming an outer hot water chamber, an intermediate chamber insulated from said hot water chamber and an inner water receiving chamber, a water chamber supported within said outer shell below the aforesaid casings and above said heat generator, a pipe leading from said water receiving chamber to said lower circulatory pipes leading from said intermediate chamber to said lower chamber, means of communication between said hot water chamber and said lower chamber, a pipe leading from said hot water chamber and extending through said outer shell, and a water supply pipe discharging into said receiving chamber.
12. In a water heater, the combination with an outer shell and a suitable heat generator, of an annular water chamber supported above said heat generator and form-

ing a central flue for the heating gases and a side return heat passage, said side return passage communicating with the said central flue at the top and bottom, a water chamber supported within said shell above said annular chamber and with said shell forming an annular passage for the heating gases, said annular passage communicating with said central flue and said side return passage, means supported in said central flue for conducting the water from said annular chamber to said upper chamber, a water supply pipe communicating with said annular chamber, a pipe leading from the bottom of said upper water chamber, a valve in the latter pipe controlling the flow of water from said upper chamber, and a valve in said water supply pipe operatively connected with the aforesaid valve.

13. In a water heater, an outer shell supported on a suitable base, a suitable heat generator supported from said base, a water receiving chamber supported within said outer shell, a primary water heating chamber supported within said shell above said heat generator and below said water receiving chamber and communicating with said water receiving chamber, a hot water chamber supported above said primary water heating chamber, means for conveying water from said primary water heating chamber to said hot water chamber, a pipe leading to said water receiving chamber from a water supply, a pipe leading from said hot water chamber, a tap closing the pipe leading to said water receiving chamber and having an extension spindle, a tap closing the pipe leading from said hot water chamber having a recess in the plug thereof adapted to receive the extension spindle of the aforesaid tap, and an adjustable cap secured to the tap leading from said hot water chamber, and operating said extension spindle to open and close the tap controlling the flow of water to the receiving chamber.

14. In a water heater, an outer shell, a hollow base supporting said outer shell and having a plurality of openings in the side wall thereof and a plurality of short tubes centrally arranged in the top thereof and forming communicating passages to the interior of said shell and projecting slightly above the upper surface of the base, a gas burner supported on said base above said tubes and having a gas supply pipe leading thereto through said outer shell, a pilot burner supported adjacent to the aforesaid burner and having a gas supply pipe leading thereto, means for controlling the flow of air through the openings in the side wall of said base, an annular water chamber supported within said outer shell above said burners and communicating with a water supply, said chamber forming a central flue for the heating gases and a side return heat

passage, said side return passage communicating with said central flue at the top and bottom, a hot water chamber supported above said annular chamber having a pipe leading 5 therefrom extending through said outer shell, and a water chamber supported in said central flue and connected to said annular chamber and said hot water chamber.

Signed at the city of Toronto, in the county of York, Province of Ontario, in 10 the Dominion of Canada, this 22nd day of February, 1908.

DAVID WILLIAM ALLMAN.
